 Dardi & Herbert PLLC(57) **CLAIM**

We claim the ornamental design for shotgun wad, as shown and described.

DESCRIPTION

FIG. 1 is a perspective view of a shotgun wad according to the invention. The opposite side being a mirror image thereto.

FIG. 2 is a perspective view of the shotgun wad of FIG. 1 with the fins in a deployed flared position after firing. The opposite side being a mirror image thereto.

FIG. 3 is an elevational view of the shotgun wad of FIG. 1. The opposite side being a mirror image thereto.

FIG. 4 is a perspective view of the shotgun wad of FIG. 1 with the fins in a flared position.

FIG. 5 is an enlarged top end view of the shotgun wad of FIG. 1; and,

FIG. 6 is an enlarged bottom end view of the shotgun wad of FIG. 1.

The broken lines depict portions of the shotgun wad that form no part of the claimed design.
